CLOSURE CAP FOR TUMBLERS, BOTTLES,
JARS, AND OTHER RECEPTACLES

Harry Ingram, Brooklyn, N. Y.

Application December 16, 1930, Serial No. 502,770

7 Claims. (Cl. 215—37)

This invention relates to closure caps for bottles, jars and other receptacles or containers and method of forming and applying the same. It has among other objects to make a cap of tin, or other suitable material possessing characteristics of relative stiffness against accidental distortion and providing an effective seal between the cap and the container to which applied and which will afford a practical reseal between the cap and container in use of the closure as a service cap after its first removal from the container.

Another object is to form a closure cap, made preferably of tin, possessing characteristics of relative stiffness, with a depending, initially vertically corrugated or fluted, apron or skirt, and with an annular groove in the under face of the closed top of the cap adjacent to said skirt, to receive and hold the upper edge of an annular or ring-shaped gasket, extending downwardly parallel with the inner face of the depending corrugated skirt or apron, between it and the wall of the container with which it is to be brought into sealing contact.

Also to provide for the lower edge of the sealing gasket to extend below the bottom edge of the depending skirt of the cap so as to guard the hand or fingers of the housewife against liability of being cut by the edge of the skirt in lifting the cap from the container for access to the interior of the container; and also other objects as hereinafter indicated.

The features specified result in the production of a stronger cap at a relatively small cost of production, with a most effective seal, and makes possible the use of the cap as a service cap after consumption of some of the contents of the container, with repeated resealing of the container to some degree throughout repeated replacement of the cap after each removal of some of the container's contents in actual service. It also makes possible the comparatively easy removal of the cap after its first installation by breaking the vacuum within the container or receptacle by insertion of a pointed instrument between the gasket and wall of the receptacle at a point opposite to one of the depressions of the corrugations in the skirt or apron so as to provide, at such temporarily displaced portion of the gasket, a vent to break the vacuum and permit easy removal of the cap from the container. The corrugations in the skirt or apron also function to permit atmospheric pressure between the skirt and gasket in the direction of the wall of the receptacle when there is vacuum in the receptacle or container so as to exert such pressure on the

gasket as will tend to maintain the gasket in sealing contact with the wall of the receptacle.

The preferred and also modified embodiments of the invention are illustrated in the accompanying drawings in which the several elements and features are shown on an enlarged scale, and in which:

Figure 1 is a side elevation of a container, such as a tumbler, embodying the invention;

Figure 2 is a plan view of Figure 1;

Figure 3 is a vertical section, enlarged, on line 3—3 of Fig. 2, looking in the direction of the arrows;

Figure 4 is a view similar to Figure 3, showing the parts as they appear after inward deflection of the cap skirt and the contents have been processed and vacuum within the container produced;

Figure 5 is a section on the line 5—5 of Figure 2, showing position of the parts before the skirt has been deflected and contents processed;

Figure 6 is a section similar to Figure 5, showing the parts after the skirt has been deflected and the contents processed;

Figure 7 is a section on line 7—7 of Figure 1, looking in the direction of the arrows;

Figure 8 is a section similar to Fig. 3 showing a modified form of cap;

Figure 9 is a view similar to Figure 4, with the modified cap;

Figure 10 is a view similar to Figure 8 showing a modified form of the top edge of the tumbler;

Figure 11 is a view similar to Figure 10, showing parts after the skirt has been deflected and contents of the tumbler have been processed;

Figure 12 is a vertical section through the upper part of a jar with a cap and gasket before the cap skirt has been deflected and before processing its contents;

Figure 13 is a vertical section, enlarged scale, through the upper portion of Fig. 12, showing parts after the cap skirt has been deflected and contents of the jar have been processed;

In the drawings the numeral 1 designates a suitable container which may be a tumbler, a bottle, a jar, a can, or other receptacle, which will have a closure cap 2 and a sealing gasket 3 for effecting a hermetic sealing of the contents of the container. Under the present invention the closure cap 2 is preferably made of tin possessing characteristics of relative stiffness, as the features of the present invention make that possible and practicable without sacrificing an effective seal and contributing to, rather than detracting from, security in holding the cap to the container and

yet facilitating removal of the cap when desired while at the same time reducing the cost of production and also providing a cap affording to a practical degree a resealing cap in use after the initial removal of the cap. The cap 2 is formed with a depending skirt or apron 4 made with vertically extending flutings or corrugations 5 and also formed at its perimeter, or substantially thereat, with a groove or recess 6 designed to receive and hold the upper portion of an annular or ring-shaped elastic gasket 3, the outer face of which lies parallel with the inner face of the depending corrugated skirt 4 and its inner face adapted to make sealing contact with the outer 10 surface of the wall of the container while the under surface of the centrally disposed top of the cap will rest or seat upon the top edge of the container wall all as illustrated. When the cap and its gasket is first slipped over the open mouth 15 of the container, the depending skirt or apron by means of a suitable tool or former, is pressed inwardly on a downward inclination or taper so as to make sealing contact with the outer surface of the wall of the container, changing the outlines of the depending skirt and gasket from what is shown in Figs. 3, 5, 8, 10 and 12 to that shown in Figs. 4, 6, 9, 11 and 13 respectively, and causing the inner face of the gasket to conform to irregularities in the outer surface of the wall of the container and enter and practically close cavities otherwise existing between the wall of the container and the inner surface of the gasket, and making an effective seal between the cap and container, as illustrated in Figs. 4, 6, 9, 11 and 13 of the drawings. The vertical corrugations give a degree of elasticity to the skirt or apron in application and removal of the cap from the container and maintain the uniformity of contour of the skirt or apron throughout its circumference so that the effective seal is not impaired, whether the contents of the container have been subjected to a processing treatment as commonly practiced in the hermetic sealing of the contents of a container, or not so processed. The vertical corrugations to the skirt or apron, under the present invention, perform the additional and important function of permitting the insertion, by a housewife, of a pointed instrument, for instance a needle like article, between the gasket and wall 50 of the container opposite the depressed portion of one of the corrugations so that the face of the gasket at the point of application of the pointed instrument will be pressed away from the wall of the container and into a corrugation of the cap skirt and thus provide a vent leading to the interior of the container at the temporarily displaced portion of the gasket away from the wall of the receptacle and break the vacuum in the receptacle and thus facilitate the removal of the cap without damage to the cap or its sealing gasket. The corrugations also under normal conditions serve to admit atmosphere between the gasket and skirt so as to exert an inwardly atmospheric pressure on the gasket in the direction 65 of the wall of the container so as to press the gasket against the wall of the container and tend to maintain sealing contact between the gasket and wall of the container as previously stated.

Figs. 4, 6, 9, 11 and 13 show the relationship 70 between the cap and its gasket and the container under a condition of vacuum in the container and the other figures without such vacuum.

In Figs. 8, 9, 10 and 11 the cap is shown formed with a depressed bead 7 adapted to seat against 75 the rounded top edge of the wall of the tumbler

or container, and the elastic gasket will be forced beneath the bead and close the space between the bead and outside of the container wall when the cap apron or skirt is given its downward and inward inclination as illustrated in Figs. 9, 11 and 13. In Figures 12 and 13 the container or jar 1 is shown as formed with an inclined face 8 at the outer surface of the wall substantially at the top and with a shoulder 9 below the inclined face so that the rubber gasket when compressed to sealing position will contact with the inclined face 8 and also lie beneath the shoulder 9 thus making an effective seal at said points and aid in holding the cap to its closing position.

It will be observed that in each form, the elastic gasket is shown as extending below the bottom edge of the depending skirt or apron. That is for the purpose of protecting or guarding the fingers or hand of the housewife, or manipulator, from possible injury by contacting with the edge 10 of the skirt in lifting the cap from off the container.

I have illustrated and described the details of the several modifications but changes may be made therein and essential features of the invention retained as sought to be defined by the appended claims.

Having described my invention and set forth its merits what I claim is:—

1. A closure for receptacles comprising a cap 30 having a depending skirt formed with axially disposed corrugations and an elastic gasket positioned between the skirt and wall of the receptacle and of a cross sectional thickness not to fill the skirt corrugations, the skirt extending 35 downwardly and inwardly to effect sealing contact between the gasket and receptacle.

2. A closure for receptacles comprising a cap having a depending skirt formed with axially disposed corrugations, and an elastic gasket positioned between the skirt and receptacle and of a cross sectional thickness not to fill the skirt corrugations, with its upper portion in contact with the inner face of the cap, the skirt extending downwardly and inwardly to effect sealing 40 contact between the gasket, receptacle and cap.

3. A closure for receptacles comprising a cap having a depending skirt, and an elastic gasket lying between the skirt and receptacle, the meeting faces of the skirt and gasket being so shaped 50 as to form axially extending air spaces between the gasket and skirt to provide for atmospheric pressure against the gasket in effecting sealing contact between the gasket and receptacle, the skirt extending downwardly and inwardly to 55 effect sealing contact between the gasket and receptacle.

4. A closure for receptacles comprising a cap having a depending skirt formed with axially disposed corrugations, and an elastic gasket positioned between the skirt and receptacle, the skirt extending downwardly and inwardly to effect sealing contact between the gasket and receptacle, the corrugations serving to receive a portion of the gasket displaced by a tool inserted between the gasket and wall of the receptacle to effect a vent to relieve a vacuum within the receptacle to facilitate removal of the cap.

5. A closure for receptacles comprising a cap having a depending skirt formed with axially disposed corrugations, and an elastic gasket positioned between the skirt and receptacle and of a cross sectional thickness not to fill the skirt corrugations, the skirt extending downwardly and inwardly to effect sealing contact between 70 75

- the elastic gasket and receptacle, apices of the corrugations making sealing contact with the elastic gasket, and the spaces between the apices constituting cavities serving to receive atmospheric pressure between the skirt and gasket to exert pressure on the gasket in direction of the wall of the receptacle to effect sealing contact of the gasket with the wall of the receptacle.
6. A closure for receptacles comprising a cap having a depending skirt formed with axially disposed corrugations, and an elastic gasket positioned between the skirt and receptacle, and of a cross sectional thickness not to fill the skirt corrugations, the skirt extending downwardly and inwardly to effect sealing contact between the gasket and receptacle, the gasket being also extended below the lower edge of the skirt prior
- 10
- 15

to application of the closure and subsequent to its removal to afford a safety guard for the hand in manipulation of the cap.

7. A closure for receptacles comprising a cap having a depending skirt formed with axially extending corrugations and with a groove in the under face of the cap adjacent to the upper portion of the skirt, and an elastic gasket having its upper end seated in said groove and held therein by its elastic characteristics, with one face disposed for contact with the inner apices of the skirt corrugations, the corrugated skirt extending downwardly and inwardly to effect sealing contact between the gasket and cap and a receptacle to which the cap is applied.
